GUSTAVE O. DEGENER, OF BROOKLYN, NEW YORK, ASSIGNOR TO ROYAL TYPEWRITER COMPANY, INC., OF NEW YORK, N. Y., A CORPORATION OF NEW YORK

TYPEWRITING MACHINE

Application filed October 31, 1928. Serial No. 316,261.

This invention relates to a line spacing mechanism for typewriters generally, although particularly the invention is directed to a key controlled power mechanism for actuating the line spacing mechanism at any point in the travel of the carriage.

In the drawings:

Figure 1 is a vertical sectional view taken in a plane fore and aft of the machine and disclosing such portions of the typewriter only as are necessary to an understanding of my invention, the view showing particularly the key controlled power mechanism and the ratchet mechanism for line spacing the platen. Figure 2 is a detail front elevation of the line spacing mechanism showing the power operated arm or lever in section, the parts being shown in their normal or inoperative positions, and

Figure 3 is a similar view but showing the parts in their operative positions.

Only so much of a typewriting machine is illustrated in the present case as is necessary to disclose the invention and its operation and the location of the various elements with respect to the other parts of the machine.

In my co-pending application Serial Number 316,260, filed Aug. 31, 1928, I disclose a key controlled power operating mechanism for effecting a line spacing movement and also a carriage return movement which is operative at any point in the carriage travel, and an independent key controlled power operated line spacing mechanism which is adapted for operation at any point in the carriage travel without, however, returning the carriage to its initial position.

My present invention relates to a different construction of key controlled power operated mechanism for effecting a line spacing operation in any position of the carriage travel and without returning the carriage to its initial position.

Accordingly, there is shown in the accompanying drawings a carriage A having a platen B and associated with the platen is a line spacing mechanism C. The line spacing mechanism C includes a vertical shaft 1 having a rock arm 2 fixed to the upper end thereof, and an operating lever or rock arm 3 fixed

to the lower end thereof. A link 4 is pivotally connected at one end to the rock arm 2, and at its other end to an arm 5 pivoted to the carriage. A spring pawl 6 is pivoted to an arm 4' for cooperation with a ratchet wheel 7 fixed to the adjacent end of the platen B to effect a line spacing movement of the platen upon movement of the operating lever 3.

A draw band 8 is connected at one end to the operating lever 3 and at its other end to a winding drum 9 fulcrumed on a bearing 10 fixed to the main frame of the machine. The construction thus far described is present in my co-pending application Serial No. 316,260, the drum 9 functioning when connected to the power shaft to effect a line spacing operation of the platen and a subsequent return movement to the carriage. Rotatable with the drum 9 is a gear 11 having teeth 12. The draw band 8 is trained around a roller 13 journaled on an axis 14 fixed to the main frame, the roller being located between the operating arm 3 and the drum 9. Disposed above the roller 13 is a bell-crank lever 15 which is fulcrumed at its angle as at 16 to the main frame of the machine. This bell-crank lever 15 includes a substantially horizontal arm 17 and a substantially vertical arm 18. A roller 19 is journaled on the upper end of the arm 18 for contact with the draw band 8 and a stop 15^a secured to the main frame of the machine cooperates with the arm 17 to limit the downward movement thereof. By reason of the roller 19 being located at the upper end of the substantially vertical arm 18 the draw band 8 is caused to assume a substantially right angular relation whereby upon movement of the arm 18 to the right as shown in Figure 3, a pull will be exerted on the draw band 8 and thereby actuate the operating arm 3 and effect a line spacing movement to the platen.

Such a pull on the draw band 8, however, can only be effected when the winding drum 9 is held against rotation. Therefore, to this end I have provided means for locking the winding drum 9 against rotation during the time the bell-crank lever 15 is being moved to bring about a line spacing operation. For this purpose I have provided a latch 20 which

is pivoted as at 21 to the frame of the machine and a link 22 is pivotally connected at one end to the latch 20 and at its other end to the vertical arm 23 of a bell-crank lever 24 which is fulcrumed at its angle as at 25 to the frame of the machine. A coil spring 26 is connected at one end to the arm 23 and at its other end to the frame of the machine and functions to normally urge the latch 20 into operative engagement with the teeth 12 of the drum gear 11. The bell-crank lever 24 is provided with an arm 27 which extends laterally under but in spaced relation to the arm 17 of the bell-crank lever 15.

5 An actuating lever or power arm 28 is fulcrumed as at 29 on the frame of the machine and a key 30 is also fulcrumed on the frame of the machine. Carried by the actuating lever or power arm 28 is a star wheel 31 which is adapted upon depression of the key 30 to be moved into operative engagement with a power shaft 32. Upon engagement of the star wheel 31 with the power shaft 32 the actuating lever or power arm 28 will be oscillated on its pivot 29 so as to move the right hand end upwardly as viewed in Figure 3. Normally, the power arm or actuating lever 28 engages the arm 27 of the bell-crank lever 24 and holds the latch 20 out of engagement 10 with the teeth 12 of the drum gear 11 and against the tension of the spring 26, as shown in Figure 2. When, however, the key 30 is depressed and the power shaft 32 raises the free end of the actuating lever 28, the spring 26 will function to swing the latch 20 into locking engagement with the teeth 12 of the drum gear 11 and thereby hold said drum against rotation. During the latter part of the movement of the power arm or actuating 15 lever 28 the arm 17 of the bell-crank lever 15 will be engaged by said actuating lever and consequently the arm 18 will be swung towards the right as shown in Figure 3, thereby exerting a pull on the draw band 8 and effecting a line spacing movement while the drum 9 is locked against rotation. As soon as this line spacing operation has been effected, the engaging point of the star wheel 31 will have been moved out of engagement with the power shaft 32 and consequently the parts 20 will be automatically returned to their normal positions as shown in Figure 2.

It is obvious that changes may be made in the precise form and arrangement of the parts without in any way departing from the spirit of the invention which is to be regarded as limited only by the scope of the appended claims.

I claim as my invention:

60 1. In a line spacing mechanism for type-writing machines having a line spacing mechanism and an operating lever therefor, the combination with said operating lever, of a winding drum, a draw band connecting the operating lever and drum, and means for

locking the drum against rotation and for exerting a pull on the band between the operating lever and the drum while the drum is locked for actuating said operating lever.

2. In a line spacing mechanism for type-writing machines having a line spacing mechanism and an operating lever therefor, the combination with said operating lever, of a winding drum, a draw band connecting the operating lever and drum, normally ineffective means for locking the drum against rotation, normally ineffective means for exerting a pull on the draw band for actuating said operating lever, and means common to both of said normally ineffective means for controlling the same. 70

3. In a line spacing mechanism for type-writing machines having a line spacing mechanism and an operating lever therefor, the combination with said operating lever, of a winding drum, a draw band connecting the operating lever and drum, means for locking the drum against rotation, normally ineffective means for exerting a pull on the draw band for actuating said operating lever, and an actuating lever cooperating with the drum locking means to normally retain the latter ineffective and adapted upon movement to render the same effective and to operate the normally ineffective draw band means. 85

4. In a line spacing mechanism for type-writing machines having a line spacing mechanism and an operating lever therefor, the combination with said operating lever, of a winding drum, a draw band connecting the operating lever and drum, means for locking the drum against rotation including a latch adapted to cooperate with the drum, a bell-crank lever, a link connecting the latch and bell-crank lever, and a spring for urging the latch into engagement with the drum, normally ineffective means for exerting a pull on the draw band for actuating said operating lever, and an actuating lever cooperating with the bell-crank lever to normally retain the latch disengaged from the drum and adapted upon movement to render the same effective and to operate the normally ineffective draw band means. 100

5. In a line spacing mechanism for type-writing machines having a line spacing mechanism and an operating lever therefor, the combination with said operating lever, of a winding drum, a draw band connecting the operating lever and drum, means for locking the drum against rotation, normally ineffective means for exerting a pull on the draw band for actuating said operating lever including a bell-crank lever, and a roller carried by one arm of the bell-crank lever and engageable with the draw band between the operating lever and the drum, and an actuating lever cooperating with the drum locking means to normally retain the latter ineffective and adapted upon movement to render the 110

same effective and to operate the bell-crank lever of the draw band pull means.

6. In a line spacing mechanism for typewriting machines having a line spacing mechanism and an operating lever therefor, the combination with said operating lever, of a winding drum, a draw band connecting the operating lever and drum, means for locking the drum against rotation including a latch adapted to cooperate with the drum, a bell-crank lever, a link connecting the latch and bell-crank lever, and a spring for urging the latch into engagement with the drum, normally ineffective means for exerting a pull on the draw band for actuating said operating lever including a bell-crank lever, a roller carried by one arm of the bell-crank lever and engageable with the draw band between the operating lever and the drum, and an actuating lever cooperating with the bell-crank lever of the drum locking means to normally retain the latch disengaged from the drum and adapted upon movement to render the same effective and to operate the bell-crank lever of the draw band pull means.

7. In a line spacing mechanism for typewriting machines having a line spacing mechanism and an operating lever therefor, the combination with said operating lever, of a winding drum, a draw band connecting the operating lever and drum, and a key controlled power mechanism for locking the drum against rotation and for exerting a pull on the band between the operating lever and the drum while the drum is locked for actuating said operating lever.

In testimony whereof, I have hereunto subscribed my name.

GUSTAVE O. DEGENER.
